Des. 203,771
Patented Feb. 15, 1966

203,771

PHONOGRAPH CABINET

Melvin H. Boldt, Glenview, Ill., assignor to Automatic
Canteen Company of America, Chicago, Ill., a corpora-
tion of Delaware

Filed Jan. 28, 1965, Ser. No. 83,616

Term of patent 14 years

(Cl. D56—4)

FIG. 1.

Des. 203,771

PAGE 2

FIG.2.

FIG. 4.

FIG. 3.

FIGURE 1 is a perspective view showing the front and right side of a phonograph cabinet embodying my new design;

FIGURE 2 is a front view in perspective thereof;

FIGURE 3 is a rear view in elevation thereof; and

FIGURE 4 is a view in elevation of the left side, the opposite or right side being substantially a mirror image thereof.

The dominant features of my design reside in the portion shown in full lines.

I claim:

The ornamental design for a phonograph cabinet, as shown and described.
